E. FISH

Washing Machine,

Patented May 25, 1832.

Fig. 2

Eya Fish.

Letters Patent Dated: May 25 1832.

The schedule referred to in these Letters Patent, and making part of the same, containing a description in the words of the said Eya Fish himself, of his improvement in the Washing Machine.

To all to whom these presents shall come:

Be it known that I, Eya Fish ofayolle in the County of Kennebec, and State of Maine, have invented a new and useful improvement in the washing machine, and that the following is a full and exact description of the construction and operation of the said machine, as invented or improved by me.

This machine is constructed to work in an oblong square box or tub, which admits of various sizes. But for ordinary use in private families, the tub may be about thirty inches in length, eighteen inches in width and twelve inches in depth; and in this tub is placed a curved apron which consists of two side pieces of some suitable kind of hard wood board, nineteen inches in length, two inches in width, and one inch in thickness.

These pieces are placed in the sides of the tub with the concave edge upwards, one end of each resting on the bottom of the tub - the other ends elevated about nine inches, and receding again at the front end of the tub, in which position they are covered with a board of some suitable kind of hard wood which extends across the whole width of the tub, and across the whole length of the side pieces excepting about three inches at

the elevated ends. The appearance of the board is flat-ted or reeded like a common wash board.

To prevent the apron from sliding on the bottom of the tub, small blocks are attached to the sides of the tub at the bottom. The reeded board of the apron is confined to the side pieces by suitable nail or screws. Rubber is constructed to operate on the apron, consisting of two side pieces about nine inches in length, three inches in width & three fourths of an inch in thickness. These pieces are placed on the apron about fourteen inches apart, the lower edge being convex & not corresponding to the curve of the apron, and the upper edges curved, or beaded, so as to reduce the width to two inches at the ends. The side pieces of the rubber may be described, as connected by several pieces of board, say three or four in number, one inch in width and three fourths of an inch in thickness, with suitable tenons on the ends that are inserted in corresponding mortises made in the side pieces so as to leave a space of one inch between them, the undersides of the pieces being reeded. The reeded surfaces of these pieces form a band with the convex edges of the side pieces, and the vacant spaces between them are occupied by rollers that are seven eighths of an inch diameter, with small judgments of iron or other hard metal in balance inserted in the ends; and the judgments must be round proportions, one fourth of an inch diameter, made in the side pieces so that the rollers project one fourth of an inch below the reeded surface of the intervening pieces; the roller is also placed at each end of the side pieces. Horizontal projections three fourths of an inch diameter, extend from the

The reeded surfaces of these pieces form a band with the convex edges of the side pieces, and the vacant spaces between them are occupied by rollers that are seven eighths of an inch diameter, with small judgments of iron or other hard metal in balance inserted in the ends; and the judgments must be round proportions, one fourth of an inch diameter, made in the side pieces so that the rollers project one fourth of an inch below the reeded surface of the intervening pieces; the roller is also placed at each end of the side pieces. Horizontal projections three fourths of an inch diameter, extend from the

side pieces of the rubber at the center (respect the length) about one inch below the upper edges.

The rubber thus circumstated, is suspended by a kind of frame work that is supported by two posts which may be two inches in width and one inch in thickness. These posts are attached to the outside of the tub, about seven inches from the rear end, extending in a vertical position, being two inches above the tub; and the posts are confined in their position by sinking the lower ends in dovetail form into the sides of the tub, or they may be confined by any other suitable kind of fastening.

The upper ends of the posts are connected by a cross piece of wood which may be either square or one and one inch and a half through, with grooves made on the ends, fitted to work in round perforations, three fourths of an inch diameter, made thin the posts, one inch below the upper ends. Two perforations which may be either round or square, are made thin the above described cross piece, about two inches from the posts and in these perforations are inserted the ends of two pieces of wood that extend in the rear about seven inches, the outside ends being about one inch and a half deep, and three fourths of an inch thick, and this three, about one inch from the rear ends, are made horizontally, round perforations, three fourths of an inch diameter and these ends are connected by a cross piece that may be either square or round, about one inch and one quarter through, with grooves on the ends fitted and in the lat-

mentioned preparations. Two round preparations three fourths of an inch diameter, or square mortices equivalent, are made like the last described cross piece, one inch and a half from the shoulder of the grub gears, and in these preparations, or mortices are inserted suitable tongs made of the ends of two pieces which extend from the last described cross piece down to the rubber as it is at rest on the apron. These pieces are about forty six inches in length, three fourths of an inch in thickness, and two inches in width at the lower end; but the width diminishes to an inch and one fourth at the upper end, the width of the pieces corresponding to the length of the tongs.

Round preparations one inch diameter, are made like the pieces last described, about an inch from the lower ends, and the ends being placed within the side pieces of the rubber are connected therewith by a roller that is one inch and one fourth through with grub gears on the ends fitted to work in the preparations last mentioned. The grub gears pass also thru the side pieces in the preparations made at the centre as before described.

The grub gears must work easily in the pieces by which the rubber is supported, but they are engaged in the pieces of the rubber by being pinned thereto.

The machine, thus constructed, may be used on any suitable frame fitted to sustain it, or it may be worked on a common work bench or any other convenient convenience.

Upon the machine the data must be prepared for working as in the usual way, and the last step in

with a sufficient quantity of warm water and soap. One large piece or several smaller pieces may be placed on the apron, soap spread on the soft surface, and the clothes applied with a rugged or gentle motion as occasion may require.

The soap and water may be removed by means of a smooth, if possible, inserted in the rear end of the tub, near the bottom.

Although specific dimensions are stated in the preceding description of the machine, yet the size and proportion of the several parts may be varied to larger or smaller at pleasure, but so as not to vary the general principle of the machine. The specific, new, and useful improvements comprised in the machine hereinbefore described, and claimed by me, as being the first inventor thereof, are the following:

1st The Rubber, as combining and preventing a surface of rollers intermixed with floated or creased pieces, and in its application and use, producing a gentle operation on the clothes, which is in a medium between a sponge and cloth, thereby producing the effect of cleaning, expediting, and properly without mauling the clothes by too heavy friction.

2nd The particular mode of suspending the rubber, being without the usual assistance of weights or springs.

3rd The general manner of combining the parts, as being now, especially in a light, compact, durable, yet of sufficient strength and elasticity, so as to be of use, and in the operation rendering every

merely the command of working, consequently requiring but little practice to become acquainted with the mode of using the machine advantageously.

In testifying that the above is a true specification of my said improvement as above stated, I have hereunto set my hand & seal the twenty fifth day of February in the year of our Lord eighteen hundred and fifty two
